UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

CAR-DOOR-OPERATING DEVICE.

1,244,770.

Specification of Letters Patent.

Patented Oct. 30, 1917.

Application filed April 17, 1917. Serial No. 162,617.

To all whom it may concern:

Be it known that I, ALLEN E. OSTRANDER, residing at Ridgewood, Bergen county, State of New Jersey, and being a citizen of the United States, have invented certain new and useful Improvements in Car-Door-Operating Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a diagrammatic view showing in elevation approximately one-half of the lower portion of a car with my car-door operating mechanism applied thereto;

25 Fig. 2 is an enlarged elevational view of a portion of the side of the car showing a plurality of doors affected by the operating mechanism therefor, parts being broken away for added clearness;

30 Fig. 3 is a transverse section taken on the line 3—3 of Fig. 2 and illustrates the door in both its closed and open positions; and

Fig. 4 is a detail vertical section through the sleeve driven by the operating shaft 35 showing the integrally formed gears on that sleeve and the means of mounting the sleeve in a bearing carried by the cross bearer.

This invention relates to operating mechanism for car doors and is of such a nature 40 that it may be applied to cars having a series of transverse underframe members, such as bolsters, cross bearers and the like, which project away from the center sill or sills to form a plurality of openings adapted to be 45 closed by bottom drop doors. An object is to provide an individual shaft for actuating each door and such shafts, while separated from each other, may be in alinement to occupy not more space than a single uninterrupted shaft. Each individual shaft is 50 provided with one or more disk-like members suitable to engage a contact member or members carried by the door in such manner as to hold the doors closed.

55 It is proposed to journal the ends of each

individual shaft in bearings which may be conveniently mounted on the cross bearers or other transverse underframe members. Gears also are to be carried by the individual shafts and they may be integrally formed with the door-supporting disks.

Suitably supported, as from the transverse underframe members, are sets of gears, those of each set meshing with the gears on different actuating shafts. It is a further purpose to employ a continuous operating shaft passing through and adapted to drive the various sets of gears that in turn drive the gears on the individual actuating shafts, such operating shaft being, therefore, common to all of the actuating shafts.

Due to the meshing gears of both the actuating and operating shafts and the peculiar bearings for the actuating shafts, the door supporting members, or disks, the gears immediately affiliated therewith and the actuating shafts are adapted to respond to the gears on the operating shaft and to move under the doors to hold them closed. When desired, these parts may be moved free of 80 the paths of the doors allowing the latter to drop and discharge lading.

The various features are set forth herein-after and all that is novel and which contributes to the usefulness of the invention 85 comes, of course, within the scope thereof.

In the drawings the car door operating mechanism has been illustrated as applied to one side of the car, but it will be understood that it may be applied to the other thereof, 90 and that it is susceptible to different arrangements than that illustrated.

Referring specifically to the parts, 1 indicates a center sill, projecting laterally from which are spaced transverse underframe 95 members, such as the bolster and cross bearers 2 and 3, respectively. An angle, or other shaped member 4, extends longitudinally of the car near the outer ends of the bolster and cross bearers, and may constitute one of 100 the side sills of the car. Mounted upon, and wider than, so as to project laterally beyond each side thereof, are top cover plates 5 for the bolster and cross bearers 2 and 3, respectively. Hinged to the center sill 1, as at 6, 105 are a plurality of doors 7, which, when in their closed positions, are adapted to extend under the projecting portions of the top cover plates 5, the side sill 4 and the center sill top cover plate 8. Each door 7 has 110

secured to it, near its outer free edge, and preferably at its opposite sides, serrated contact members 9. Two such contact members 9 have been shown as being applied to each door 7 and each is adapted to be engaged by a serrated disk-like roller 10.

An individual actuating shaft 11 is supplied for each door and upon each of the shafts is mounted a pair of the disk-like members 10. The opposite ends of each individual actuating shaft 11 are mounted in bearings 12 and 13 preferably carried by the cross bearers 3. The bearings 12 and 13 each have similar tread surfaces 14, but, as illustrated in Fig. 2, may be otherwise differently fashioned and variously mounted upon the cross bearers 3. It is obvious that while bearings 12 are secured to the webs of cross bearers 3 and bearings 13 are mounted on the lower flanges thereof, the latter bearings may be duplicates of bearings 12 and be secured to the webs of the cross bearers, if desired. Also mounted upon each individual actuating shaft 11 is a pair of gear wheels 15, and one of the advantages is that the serrated disks 10 and gears 15 may be cast as integers. It will, however, be understood that a different number of door-carried serrated contact members 9 and disks 10 than that shown may be used, that they may be differently disposed and that the gears 15 may be separately formed and not necessarily in close association with disks 10.

Meshing with the gears 15 carried by the actuating shafts 11 are other gear wheels 16.

As best shown in Fig. 4, it is convenient and economical to connect pairs of the gears 16 by a sleeve 17 and said connected gears and sleeve may be integrally cast. Each sleeve 17 forms a journal that is mounted in a bearing 18, said bearings being secured to the bottom flanges of the cross bearers 3, as shown in Figs. 2 and 4. In the drawings, the bearings 18 are illustrated as being of the pillow block type having removable caps. Bearings 18 are secured to the bottom flanges of cross bearers 3 by means securing the actuating shaft bearings 13 to those flanges, by choice, thereby making a compact and mutual reinforcing disposition of the two types of bearings and the cross bearer flanges that are interposed therebetween.

The connected pairs or sets of gear wheels 16 are adapted to be simultaneously responsive to a continuous operating shaft 19 that extends through a plurality or all of them. It therefore becomes apparent that the operating shaft 19 is common to all of the actuating shafts 11 and through the gears 16 and 15 operates shafts 11 in unison.

Operating shaft 19 extends toward the car end and it may terminate at any point beyond the series of successively spaced doors 7 that are positioned between the successively spaced transverse underframe

members, said shaft having been shown as being extended to the end of the car. Such end, or each end, of operating shaft 19 may be journaled in a bearing 20 and have rigidly mounted thereon a ratchet wheel 21 adapted to be engaged by a retroaction pawl 22 to prevent unintentional reverse rotation of said shaft.

Extending beyond ratchet wheel 21 is a portion of shaft 19 adapted to receive any suitable means for rotating it, such means either being a lever or appropriate ratchet wheel operating mechanism.

One of the door hinges 23, preferably the central one, may extend toward the forward end of the door 7, stiffening such door, and in its outer portion being bent downwardly to form a bracket 24 in which may be mounted an eye-bolt 25. Secured to eye-bolt 25 of bracket 24 of each door, is a winding chain 26, which, when the door is closed, is wound upon the individual actuating shaft 11 immediately associated with that door, the opposite end of the chain being suitably secured to such shaft 11.

The tread surfaces 14 of the bearings 12 and 13 are curved and concentric with the axis of the operating shaft 19, from which it is apparent that the serrated disks 10 and the gear wheels 15 are rotatable concentrically both about the axes of individual actuating shafts 11 and that of operating shaft 19. The flange that furnishes the tread surface 14 is curved to substantially create a slot-like formation in each bearing 12, the terminals of said flange being spaced apart so that the end of the actuating shaft may be readily inserted to rest upon the bearing surface 14.

There are bottom cover plates extending under the center sill 1 at each cross bearer and outwardly toward the sides of the car for a considerable distance. Under the center sill 1, bottom cover plate 27 is in the form of a flat sheet, but as it progresses outwardly it changes into an inverted channel-shaped structure 27^a, to opposite sides of which are secured depending stops 28. Said stops are provided with outstanding flanges adapted to receive side flanges of the doors 7 when the doors are in their open loading-discharging positions. To prevent accidental distortion of the structure, stops 28 may be connected by a tie plate 29.

The operation of the car door operating mechanism is as follows:

Assuming that the doors are in the closed position, as shown in the full lines in the drawings, they may be opened by disengaging pawl 22 from ratchet 21, shown in Fig. 1. A lever or other door-operating mechanism is applied to the end of operating shaft 19 and caused to rotate it contraclockwise, thereby rotating the gear wheels 16 in the same direction. The teeth of gear wheels 18

16 apply power to the teeth of the gears 15 carried on the various individual actuating shaft, rotating said gears 15 in a clockwise direction. Diametrically opposite to the power application to gear wheels 15, the serrated disks 10 are in contact, when the doors are closed, with the serrated surfaces of the door-carried contact members 9, and serrated disks 10 being rotated with gear wheels 15 roll outwardly on the serrated surfaces of contact members 9, in much the same manner as a hoop is rolled. That is to say, disks 10 make a tangential contact with the serrated surfaces of door-carried contact members 9 and the power is applied to the periphery of the disks 10 to roll it on those contact members in the same manner that a hoop rests upon the ground and has power applied to its periphery to roll it. Disks 10, and consequently gears 15 and the individual actuating shafts 11, therefore, revolve and move outwardly, the door-carried contact member 9 and the door 7 themselves moving downwardly as the disks 10 move outwardly, assisting in the latter portion of the outward movement of disks 10 in causing said disks to assume the dot and dash positions indicated in Fig. 3.

In traveling outwardly, the disks 10 rotate clockwise and unwind the chain from the individual door actuating shafts 11 until such time as the doors are free to pass beyond disks 10. Thereafter, the weight of the doors and that of the lading they sustain, continue to rotate the combined disks 10 and gears 15 allowing the doors to drop until brought to rest by engaging the stops 28.

It is to be noted that, while the teeth of gears 16 are circularly arranged, they, nevertheless, correspond, in a sense, to a straight rack for the reason that the tread surface 14 of the bearings 12 and 13 are concentric with the pitch circle of the teeth of gears 16. Hence, due to the parallelism of the tread surfaces 14 and the teeth of gear wheels 16, notwithstanding their curvature, the gears 15 meshing with gears 16 may continuously roll on the periphery of gears 16 quite as freely and truly as a gear wheel could roll upon a straight rack. Resulting from this freedom to roll, the chains 26 of the falling doors ultimately roll the gears 15 on the actuating shafts 11 back into the full line positions indicated in Fig. 3.

The doors having come to the dot and dash positions illustrated in Fig. 3 and the lading having been discharged, the doors may be returned to their closed full line positions by turning operating shaft 19 in a clockwise direction. The weight of the doors transmitted to the individual actuating shafts 11 by chains 26 will hold said shafts 11 in tight frictional contact with the tread surfaces 14. Due to the meshed

engagement of gears 15 and 16, the clockwise movement of shaft 19 results in a counterclockwise rotation of the gears 15, serrated disks 10 and the individual actuating shafts 11. The latter shafts, therefore, have no alternative but to turn counterclockwise in frictional engagement with tread surfaces 14 of bearings 12 and 13. There is at this time no nullifying contact of serrated disks 10 with any other part, and actuating shafts 11 roll outwardly to the dot and dash line position indicated in Fig. 3, meanwhile winding up the chains. When the chains are of greater length than may be taken up by the number of revolutions necessary to move actuating shafts 11 from their inner to their outer positions, said shafts will be caused to continue to rotate until the doors are lifted.

The doors having become lifted they afford reaction from their pivots 6, through themselves and through chains 26, thereby causing individual actuating shafts 11 to travel inwardly in taking up the remainder of the chains 26. Consequently, the serrated disks are again brought into the full line closed position indicated in Fig. 3, whereupon they may be drawn home by continued pressure on the operating shaft 19. Having assumed the positions illustrated in Fig. 3, the serrated disks again hold the doors 7 in load-sustaining closed positions.

Because of the ability of the gear wheels 15 to rotate so as to travel on the periphery of gear wheel 16, they are self-accommodating to any impulses which would tend to interfere with their rotation were they mounted for rotation alone. Also the webs of the cross bearers project between the individual actuating shafts 11, isolating one from the other, and because of this isolation any particular shaft may be removed for repairs or substitution independently of the other shafts 11.

What I claim is:

1. In combination, a drop door, spaced parallel shafts and geared wheels co-operatively connecting the same, one of said wheels being responsive to another to be moved clear of said door to permit it to drop and to be moved under said door to hold it closed.
2. In combination, a drop door, spaced shafts, meshing gear wheels co-operatively connecting the same and door-lifting means operable by one of said shafts, one of said wheels being movable out of the path of said door and being adapted to turn the last mentioned shaft to close said door and to thereafter be positioned to hold said door closed.
3. In combination, a door, separated bearings having tread surfaces, a shaft bearing on said surfaces, a wheel mounted on said

shaft, another shaft extending with the first shaft, and means adapted to be actuated by the second-mentioned shaft in opposite directions to operate the first mentioned shaft 5 and to cause it to traverse said tread surfaces and move said wheel into and out of door-closing position.

4. In combination, successive doors and winding shafts connected therewith, wheels 10 mounted on said shafts, an operating shaft common to said winding shafts, and means operable by the operating shaft adapted to move said winding shafts and wheels out of the paths of said doors to permit them to 15 drop and to move said wheels into position to support said doors when closed.

5. In combination in a car, connected drop doors and winding shafts, spaced transverse underframe members interposed between 20 successive doors and winding shafts, bearings for said shafts on said members, wheels on said shafts, an operating shaft extending to be juxtaposed to the different winding shafts, and means operable by said operating shaft adapted to move said winding shafts and wheels to permit said doors to drop and also to cause said wheels to hold the doors closed.

6. In combination in a car, successively 30 arranged doors, an actuating shaft for each door connected therewith, door-supporting devices mounted on the actuating shafts, an operating shaft common to the actuating shafts, means operable by said operating shaft adapted to move said actuating shafts in opposite directions to position said door-supporting devices to either release or hold said doors closed.

7. In combination, a hinged door having 40 a contact member, a pair of parallel shafts, means for driving one shaft from the other, and a door-supporting device adapted to engage said contact member to hold said door closed and movable concentrically 45 about the axes of both shafts to release said door.

8. In combination, a hinged door, a contact member thereon, a shaft, fixedly positioned bearings for the ends thereof, a circular door-supporting member mounted on 50 said shaft, and means for applying power to the periphery of said door-supporting member to rotate the same and move it into and out of circumferential engagement with 55 said contact member to, respectively, support and release said door.

9. In combination, a hinged door having 60 a contact member, fixedly positioned bearings having tread surfaces, a shaft connected to said door, a round door-supporting member mounted on said shaft and adapted to circumferentially engage said contact member to hold said door closed, and means for applying power to the periphery of said 65 door-supporting member to rotate it out of

engagement with said contact member and to roll said shaft on said tread surfaces to close said door.

10. In combination in a railway car, successive transverse underframe members, drop doors positioned between the same, individual shafts for and connected with said doors, an operating shaft common to the individual shafts, bearings on said underframe members for the various shafts, meshing gears connecting said operating and individual shafts and door-supporting disks on the latter shafts adapted to be moved under and also away from said doors. 70

11. In combination in a railway car, a plurality of successively spaced doors, each having a plurality of contact members, an actuating shaft for each door operably connected therewith, circular door-supporting members and gears mounted on said actuating shafts, a single operating shaft, gears thereon meshing with the gears on said actuating shafts, and transverse underframe members supporting said shafts and extending between said doors and the actuating shafts, said door-supporting members being movable into engagement with said contact members and also clear of said doors. 85

12. In combination in a railway car, a transverse underframe member having a lower flange, a door to one side of said member, a pair of parallel shafts one operably connected with said door and the other being an operating shaft, gears on said shafts and in mesh, a round door-support on the shaft connected with the door, movable under and clear of said door, and a bearing for each shaft positioned, respectively, above and below the flange of said underframe member. 95

13. In combination, a drop door, a contact member thereon, an actuating shaft operably connected with said door, an operating shaft parallel with said actuating shaft, a door-supporting member mounted on the actuating shaft and comprising a roller 100 adapted to engage said contact member to hold the door closed and a gear portion, and a gear on said operating shaft meshing with the gear portion of said door-supporting member adapted to move the last named member clear of said door. 110

14. In combination, a pair of spaced doors, a rigid frame member therebetween, an individual actuating shaft for each door, door-supporting members and gears mounted on adjoining ends of said actuating shafts, a sleeve member supported from said frame member and provided with spaced gears each meshing with a gear on a different actuating shaft and an operating shaft passing through said sleeve member in driving relation thereto. 120

15. In combination, a pair of spaced doors, a rigid frame member therebetween, 125

door - supporting - and - actuating means including an individual shaft for each door and gears on adjoining ends of said shafts, a bearing on said frame member, an integral member comprising a sleeve mounted in said bearing and spaced gears each in mesh with the gear of one actuating shaft only.

16. In combination, a pair of doors having contact members, door-supporting-and-actuating means including an actuating shaft for each door and integrally formed gears and disks on adjoining end portions

of said shafts, for engagement with said contact members, a sleeve having integral gears meshing with the gears of said actuating shafts, and an operating shaft adapted to drive said sleeve. 15

In witness whereof I have hereunto set my hand in the presence of two witnesses.

ALLEN E. OSTRANDER.
